METHOD OF MAKING CRÊPE PAPER

Filed Oct. 20, 1920

Patented Sept. 23, 1924.

1,509,418

UNITED STATES PATENT OFFICE.

AUSTIN E. COFRIN, OF GREEN BAY, WISCONSIN.

METHOD OF MAKING CRÊPE PAPER.

Application filed October 20, 1920. Serial No. 418,221.

To all whom it may concern:

Be it known that I, AUSTIN E. COFRIN, a citizen of the United States, and resident of Green Bay, in the county of Brown and State of Wisconsin, have invented certain new and useful Improvements in Methods of Making Crêpe Paper; and I do hereby declare that the following is a full, clear, and exact description thereof.

My invention relates to new and useful improvements in the methods of making crêpe paper.

Heretofore, crêpe paper has been made by a process which consisted of a series of disconnected steps or operations. For instance, the web of paper from the paper making machine after being dried is cut into different widths or into strips of any desired width and wound on rolls. These rolls are then taken to a storage room or the like and used as necessity demands, it obviously being necessary when such use occurs to unwind the rolls and feed the strips through a crêping machine. In this latter machine the paper is moistened and crêped, and thereafter is subsequently dried and wound upon other rolls.

This prevalent method of manufacturing crêpe paper is not only expensive, but requires a considerable amount of time on account of the unnecessary number of operations. I have discovered that not only a much better grade of crêpe paper can be manufactured, but the same can be made at a considerable reduction in cost and in a much shorter time by this simpler method. Therefore, it is the principal object of my invention to provide a process of crêping paper which will consist of a relatively few number of steps, all of which may be performed within a relatively short space of time.

A further object of my invention is to provide a process which will be continuous, that is to say the crêping is accomplished immediately after the web of paper is passed from the paper making machine.

A further object of the invention is to provide a process of this character including as one of its operative steps, the moistening of the paper web to a predetermined degree immediately prior to the crêping operation.

To the accomplishment of the objects above stated and others that will become

apparent as the description proceeds, the invention comprises the steps hereinafter described and particularly pointed out in the appended claims. The annexed drawing illustrates by way of example an apparatus with which the method can be carried into effect.

The figure shown in the drawing is a diagrammatical view of rollers and endless bands adapted to carry out the various steps of the improved method.

Referring to the drawing in detail, the numeral 1 designates an endless band which is trained around suitable rollers 2, one of which I have shown in the drawing, which constitutes a conveying means for the paper web 3 which is to be crêped. The paper 3 is delivered to the endless band from the paper making machine and then to the lower run of a felt band 4 which passes around a plurality of rollers 5 which are so arranged that the paper will be conveyed in the appropriate direction. In order to insure the engagement of the paper 3 with the felt band 4 I have provided a roller 6^a adapted to coat with one of the lower rollers 5.

Arranged above and adjacent the continuous felt band 4 is a cylindrical drum 6 interiorly heated so as to dry the paper 3 which passes around the exterior of the drum. The drum may be heated by any suitable or convenient means, and as a matter of practice steam is employed for such purpose. As the result of the heating the side of the paper web in engagement with the drum becomes smooth and is provided with a glazed finish.

When leaving the drum 6 the paper passes around a guide roller 7 to an endless band 8, trained around a pair of rollers 9, and is then conducted over a number of rollers 10, which are rotatably mounted within troughs 11, filled with water so that the paper web in contacting with the top-most portion of the rollers 10 receives the proper degree of wetting necessary to obtain the crimping of the paper, and in order to insure the correct degree of wetting which the paper receives I have arranged above one of the rollers 10 a roller 7^a which maintains a certain pressure upon the paper.

Arranged adjacent the last of the rollers 10 and adapted to receive the paper therefrom is a crêping plate 12, which simultane-

ously effects the crimping of the paper due to the fact that the plate 12 is provided with a blunt edge.

From this plate 12, the crimped and moistened paper is then conducted around a plurality of heated rollers 13 to become thoroughly dried, there being a plurality of endless bands 14 and 15, which are trained around rollers 16 and 17 respectively, and which are adapted to hold the paper in contact with the exterior of the heating rollers.

It will be apparent from the foregoing description, that the invention consists in the combination of a series of steps, the web of paper from the drying means of the paper making machine being run directly to the crêping machine in an uncut full width condition without the intervention of any intermediate steps, after which and while the full width web is passing through the crêping machine, it is moistened, then crêped, and finally dried and wound on suitable rolls. The drying and winding may, or may not, be carried out in the crêping machine. Thus in this method of manufacturing crêpe paper, the paper materials are put through a continuous, unbroken series of operations from the time the pulp is fed to the paper making machine to the final winding of the crêped and dried web on to the roll. Obviously this invention reduces the number of steps which have heretofore been considered necessary in the manufacturing of crêpe paper, and as a result, such paper can be made quite inexpensively and more quickly than heretofore.

One of the principal points to be considered in this connection is that the full width of the paper web as it comes from the paper making machine is fed in an uncut condition through the crêping machine, and if there is any cutting done it is not carried out until after the paper has been crêped and dried. The best results have been obtained and the best crêpe paper made by moistening the paper web after it comes from the paper making machine to a certain predetermined degree. That is to say if the paper web is 45% dry the best quality of crêpe is obtained.

Having thus fully described my invention, what I claim as new, and desire to secure by Letters Patent is:—

1. The method of making and crêping paper as a continuous process which comprises forming the paper stuff into a web, drying the web, moistening the dried web as it passes from the drying apparatus and crêping the thus uniformly moistened web before again drying.

2. The method of making and crêping paper as a continuous process which comprises forming the paper stuff into a web, drying the web with application of heat, moistening the dried web while in a heated condition and crêping the thus uniformly moistened web.

In testimony that I claim the foregoing I have hereunto set my hand at Green Bay, in the county of Brown and State of Wisconsin.

AUSTIN E. COFRIN.
